IGNITION SYSTEM

George H. Marmont, Detroit, Mich., assignor to
 Bendix Aviation Corporation, Detroit, Mich., a
 corporation of Delaware

Application April 29, 1944, Serial No. 533,383

4 Claims. (Cl. 123—148)

This invention relates to ignition systems, and more particularly to an ignition system for an internal combustion engine.

Broadly the invention comprehends an ignition system for a prime mover including a cathode ray tube having a heated cathode, an arrangement of electrodes serving to attract electrons from the cathode and to project them in a beam, a distributor including oriented contacts, and a magnet for deflecting the electron beam and causing it to sweep over the contacts. The contacts are spaced to correspond to the firing times of the cylinders of the prime mover and are connected through relay circuits to the spark plugs in the heads of the cylinders.

An object of the invention is to provide an ignition system for an internal combustion engine including means for utilizing a low current to trigger a circuit carrying high voltage operative to discharge across the gap of a spark plug.

Another object of the invention is to provide an ignition system for an internal combustion engine characterized in that an electron beam is utilized to successively trigger a series of high voltage circuits, each operative to discharge across the gap of a spark plug.

Another object of the invention is to provide an ignition system for an internal combustion engine characterized in that an electron beam may be deflected to sweep over oriented contacts connected to a series of high voltage circuits so as to successively trigger the circuits and cause a discharge across the gaps of spark plugs.

A further object of the invention is to provide an ignition system for an internal combustion engine characterized in that an electron beam deflected by the poles of a rotatable magnet geared to the crankshaft of the engine serves to successively trigger relay circuits so as to cause discharges therefrom across the gaps of spark plugs associated with the engine.

Yet a further object of the invention is to provide an ignition system for an internal combustion engine characterized in that an electron beam may be controlled to successively trigger a series of relay circuits, each including a thyratron tube, a condenser, and the primary of a transformer connected in series, and a large resistance connected to a positive potential source for building up a charge in the condenser which discharges through the primary and tube when the circuit is triggered so that high voltage may be induced in the secondary of the transformer to cause a discharge across the gap of a spark plug.

Other objects and advantages of the invention will appear from the following description taken in connection with the drawing forming a part of this specification, and in which:

5 Fig. 1 is a longitudinal sectional view illustrating the control for an ignition system embodying the invention; and

Fig. 2 is a diagrammatical illustration of the system.

10 Referring to the drawing for more specific details of the invention, 10 represents a shaft which may be suitably geared to the crankshaft of an internal combustion engine. The shaft 10 is connected through a conventional timer 12 to a spindle 14 supporting a magnet 16 for rotation therewith.

15 A stationary shell or case 18 of magnetically shielding material enclosing the magnet 16 has suitably secured therein a collar 20 of any desirable insulating material, and binding posts 22 are arranged on the collar in spaced relation to one another. A metallic shell 24 fixedly secured to the collar 20 extends therefrom concentrically of the case between the poles of the magnet 16, and a base 26 is fitted in the shell.

20 A cathode ray tube 28 having the characteristics of the tube described in my co-pending application filed on even date herewith, is fitted on the base 26 in the shell 24 and is supported by the collar 20. The tube has thereon a base 30 received by an opening in a cover plate 32 on the case 18.

25 A cable 34 leading from a suitable source of electrical supply extends through an opening in the cover plate 32 into the case 18, and the leads 36 thereof are connected to the binding posts 22, which in turn are connected by leads 38 to the sockets of the base 26 receiving the tube, and another cable 40 leading to a group 30 of electrical circuits, to be hereinafter described, extends through a cap 42 fitted on the base 30 protruding through the cover plate 32 of the case 18, and the leads 44 thereof are connected to sockets for the reception of the plugs in the base

45 30. As shown diagrammatically, the cathode ray tube 28 includes a heater 46, a cathode 48, a grid 50, and a group of anodes 52 constituting an electron gun which serves to attract electrons from the cathode and to focus them in a beam down the axis of the tube, and the magnet 16 rotating around the tube serves to deflect the beam.

50 The cathode ray tube is characterized in that a distributor 54 supported in the tube has thereon

a plurality of spaced distributor plates 56 over which the focused electron beam sweeps when deflected by the poles of the magnet as the poles rotate about the tube.

Each distributor plate 56 is connected to a relay circuit as by a lead 60. Since these relay circuits are identical, a description of one will suffice for all.

As shown, a tube 82 of the thyratron type includes a heater 84 for heating a cathode 66, a shielded grid 88, and a plate 70. The lead 60 is connected to the grid 88. The plate 70 is connected to one terminal of a condenser 72. The plate 70 is also connected to a source of substantially constant voltage 74 by a resistor 76. The other terminal of the condenser 72 is connected to one terminal of the primary 78 of a transformer 80, and the other terminal of the primary is grounded at 82. The cathode 66 is also grounded at 82. The grid 88 is connected to a suitable source of negative bias 84 by a grid leak resistor 86. The grid is also by-passed to ground by a small condenser 88. The secondary 90 of the transformer 80 has its terminals connected to a spark plug 92, and a capacitance 94 represents the stray capacity of the secondary 90 of the transformer and its leads to the spark plug.

In the circuit illustrated, the plates 56 of the distributor tube assume a positive potential, due to secondary electron emission from the plates, when the electron beam impinges on the plates. This action causes the plate 60 to assume a more positive potential when the electron beam passes over its plate. The grid 88 is thereby driven sufficiently positive, relative to its bias potential, to turn on the thyratron 82.

It is to be understood that with other types of gas tubes, such as a cold cathode tube, an adequate negative pulse from the distributor would be effective for purposes of triggering the gas tube. The distributor shown is capable of producing such negative pulses when the proper potential is applied to the distributor plates.

The characteristic of a thyratron tube is that, once turned on, conduction continues until the anode or plate potential of the tube reaches a certain minimum value. While conducting, it possesses a low resistance. Therefore, if, as shown in the drawing, a charged condenser and the primary of a transformer 80 are connected in series with the tube, the condenser will discharge through the transformer 80 and tube, when the latter is turned on, with a very small loss of energy in the tube. Charge is built up across the condenser while the tube is off, by way of the

large resistor 76 connected to a positive potential source 74.

While this invention has been described in connection with certain specific embodiments, the principle involved is susceptible of numerous other applications that will readily occur to persons skilled in the art. The invention is, therefore, to be limited only as indicated by the scope of the appended claims.

Having thus described the various features of the invention, what I claim as new and desire to secure by Letters Patent is:

1. An ignition system for an internal combustion engine comprising means for projecting an electron beam, a distributor having oriented contacts, means driven by the engine for moving the beam successively over the contacts, a relay circuit connected to each of the contacts, and a spark plug coupled to each relay circuit.

2. An ignition system for an internal combustion engine comprising means for projecting an electron beam, a distributor having oriented contacts, magnetic means driven by the engine for moving the beam successively over the contacts, a relay circuit connected to each of the contacts, and a spark plug coupled to each relay circuit.

3. An ignition system for an internal combustion engine comprising means for projecting an electron beam, a distributor having oriented contacts thereon, magnetic means driven by the engine for sweeping the beam over the contacts, relay circuits connected to the contacts, each circuit including a tube, a condenser and the primary of a transformer connected in series, and a large resistance connected to a positive potential source, and a spark plug connected to the secondary of the transformer.

4. An ignition system for an internal combustion engine comprising a stationary case, a shaft driven by the engine, a stub shaft rotatable in the case, a timer connecting the shafts, a shielded tube supported in the case, a magnet on the stub shaft rotatable around the tube, a heated cathode in the tube for supplying electrons, a gun for attracting the electrons from the cathode and projecting them in a beam, a distributor having thereon oriented contacts successively receiving the beam as it sweeps over the distributor under the influence of the magnet, a relay circuit connected to each of the contacts, each circuit including a tube, a condenser, and the primary of a transformer connected in series and a large resistance connected to a positive potential source, and a spark plug connected to the terminals of the secondary of the transformer.

GEORGE H. MARMONT.
